Philip Brown Rice Kennedy

UNITED STATES PATENT OFFICE.

LE ROY ROOT, OF NEW YORK, N. Y., ASSIGNOR TO SCOVILL MANUFACTURING COMPANY, A CORPORATION OF CONNECTICUT.

POWDER BOX.

Application filed February 28, 1922. Serial No. 539,918.

To all whom it may concern:

Be it known that I, Le Roy Root, a citizen of the United States, residing at New York city, county of Kings, and State of New York, have invented certain new and useful Improvements in Powder Boxes, fully described and represented in the following specification and the accompanying drawings, forming a part of the same.

10 This invention relates to certain improvements in boxes for containing loose powder and particularly for face powder.

These boxes are widely used by ladies for carrying face powder and are of a size to conveniently fit in a hand bag, pocket book or the like, the boxes also generally being capacitated to contain a powder puff or the like for applying the powder. The preferable way of using face powder is in the loose condition, as powder in this form is purer and most users have a particular kind or brand of powder which they prefer to use. If, however, powder is carried loosely in a box with a puff much waste occurs by the spilling of the powder either when the puff is used to take it from the box, or the box accidentally coming open.

For avoiding this wastage of loose powder the powder manufacturers have made up their face powders in molded cakes called compacts formed of the powder and a binder, these cakes being fitted into the boxes. These cakes or compacts are open to various objections. In the first place the powder is adulterated by the use of the binder necessary to hold the powder in the form of a compact. Furthermore these cakes are very brittle and are liable to be broken either in shipping or in loading them into the boxes. Furthermore they are very liable to break after they have been used to some extent and worn down and having once been broken are usually unfit for use.

45 It is the object of the present invention to provide a powder box in which is secured a refillable container or member provided with powder distributing orifices and which shall be leak proof, that is the container will be formed or provided with means which will prevent the escape of powder from the container, and consequently from the box, except through the discharge orifices so that loose powder may

be used instead of the compacts above referred to. 55

A further object of the invention is to produce a construction in which the container may be easily and quickly filled with powder. 60

A further object of the invention is to provide a construction in which the container will be formed with a flexible part by lightly tapping or striking which powder will be ejected through the powder orifices so that it can be readily taken up by a powder puff. 65

A further object of the invention is to provide a cheap compact structure which may be easily carried in a hand bag, pocket book or the like, and which, if desired, may be of polished material or capacitated to carry a small mirror. 70

With these and other objects not specifically referred to in view, the invention consists in certain novel parts, arrangements and combinations, a detail description of which will be given in connection with the accompanying drawings, and the novel features thereof pointed out in the claims hereunto annexed. 75

In these drawings—

Figure 1 is a vertical sectional view of the improved box with the puff therein, the box being shown with the cover closed. 85

Figure 2 is a side view, partly in section, of the box shown in Fig. 1, the cover of the box being shown open and the puff removed.

Figure 3 is a sectional plan view taken on the line 3—3 of Fig. 1. 90

Figure 4 is a sectional view showing one means for rendering the powder container leak proof, certain of the parts being in the position occupied when filling the container. 95

Figure 5 is a view similar to Fig. 4 showing the container filled and ready to be put in the box.

Figure 6 is a plan view of Fig. 5 looking down on the structure shown in that figure. 100

Figure 7 is a sectional view showing a modification of the means for holding a removable container in the box.

Figure 8 is a view similar to Fig. 5 showing a modification in the method of closing the container after refilling. 105

Referring now to these drawings, the im-

proved structure will include a box 1, having a cover 2 hinged to the box by a hinge indicated at 3. This box will preferably be circular in shape and of a size convenient 5 for carrying in a hand bag, pocket book or the like. This box may be of any suitable or desired material, but preferably will be of some cheap metal, as brass. The inside of the cover may, if desired, be polished so 10 as to afford a reflecting surface, or may be provided, if desired, with a small mirror, not shown.

Carried in this box is a powder container which is provided with powder distributing orifices and with means for refilling the container, the container being so constructed and arranged as to be leak proof, that is, so that no powder can escape therefrom except through the distributing orifices. This 15 container may take a wide range of forms, and various means may be provided for effecting the refilling and leak proof functions of the container. While the container might be arranged so as to be permanently secured 20 in the box and refilled without removal therefrom, in the best constructions this container is removable from the box for the purpose of refilling and means are provided for removably securing the container in the 25 box to prevent accidental displacement. In the specific example illustrated, this container is in the form of a plate 4 provided with distributing orifices 5, these distributing orifices being provided in suitable numbers and preferably arranged in concentric circles near the center of the plate. These 30 orifices furnish egress for the powder so that the powder can be taken up on a puff indicated at 6.

In the best constructions this distributing plate will be arranged so as to yield somewhat so that by lightly tapping it powder is forced through the orifices spreading onto the unperforated parts of the plate between 40 the orifices when it can be readily taken up by the puff. To effect this the plate, as before stated which is of metal, is somewhat bowed or concave, as indicated at 7. The yielding action of the plate may also be 45 assisted, if desired, by a coil spring 9 taking between the bottom of the box and a flange 10 bent down at the edges of the plate. The container is, in the particular construction illustrated, filled from the back, and means 50 are provided for making the container leak proof after it is filled. In the particular construction illustrated, this is effected by providing a piece of paper, cloth, or the like, of sufficient fineness to prevent the powder 55 sifting therethrough, this paper or cloth being turned in at 11 and secured to the inner face of the plate. This paper or cloth thus makes in effect a pocket, as shown in Fig. 4, into which the powder may be placed. 60 The powder is held in position in the pocket

by a retainer in the form of a disk 12 of cardboard or other suitable material, and this in turn is held in place in the construction shown in Figs. 1 to 6 by folding in the outer edges 13 of the paper or cloth 70 on to the retainer 12, as shown clearly in Fig. 6. If desired, a draw string, such as shown at 14 in Fig. 8, may be employed for securing the paper around the edges of the cardboard. 75

The container is set into the box, as shown in Fig. 1, with the inturned paper or cloth 13 next the bottom of the box. With this construction the powder is prevented from escaping from the container and consequently from the box except through the distributing orifices and these are kept closed when in use by the puff 6, it being understood that the box and container are capacitated so as to snugly hold the puff and the container when the box is closed. This snug holding of the puff and container in the box is also aided by the spring 9, before referred to. 80

When, as in the construction illustrated, the container is removably secured in the box means will be provided for holding it in position. While these means may be of various characters as shown in Fig. 1, there is provided a piece of spring wire 15 which bears against the top edge of the plate 4 and against an abutment in the form of a circular flange 16 formed in the interior of the box body. In this construction the holding wire 15 is pressed down and removed from engagement with the abutment 16 so that it can be removed from the box. When this is done the container may be readily removed from position for refilling. Under some circumstances it will be desirable to omit the wire 15 and to provide the container with holding projections which will frictionally engage the box sides. Such a construction is illustrated in Fig. 7 in which the side flange 17 of the plate is extended downwardly for some distance and at two opposite points is punched out to form projections 18 which frictionally engage with the sides of the box intermediate the hinge 3 and the fastening snap 19 by which the cover 2 of the box is secured to the body 1. These boxes being of metal are somewhat resilient and by pressing in the front edge 20 of the box body the cover is released and this pressure slightly deforms the box spreading it at the point where the projections 18 engage the sides, thus freeing the projections so that the container can be readily lifted out of the box. 100

While the invention has been shown and described in its preferred form, it will be understood that various changes and variations may be made in the form of the container, and the means for securing it in the box and for refilling the container with pow- 105 110 115 120 125 130

der, and that the invention is not to be restricted to the specific construction shown and described.

What I claim is:

- 5 1. A vanity box for containing loose powder having a bottom compartment and a cover, a powder container positioned in the bottom of the box and bodily removable therefrom, said container comprising a flexible plate formed with a downwardly extending flange and having powder distributing orifices, a pocket open against the plate and secured to the plate under its outer edge the other end of the pocket being of 10 flexible material and a thin disk closing the end of the pocket, the material of the pocket being removably inturned under the lower edge of the disk, a spring arranged outside the container bearing against the under side of the flange, and resilient means 15 independent of the spring for removably holding the container and associated parts in the bottom of the box.
- 10 2. A vanity box for containing loose powder having a bottom compartment and a cover, a powder container positioned in the bottom of the box and bodily removable 20 therefrom, said container comprising a flexible plate formed with a downwardly extending flange and having powder distributing orifices, a pocket open against the plate and secured to the plate under its outer edge the other end of the pocket being of 25 flexible material and a thin disk closing the end of the pocket, the material of the pocket being removably inturned under the lower edge of the disk, a spring arranged outside the container bearing against the under side of the flange.
- 15 2. A vanity box for containing loose powder having a bottom compartment and a cover, a powder container positioned in the bottom of the box and bodily removable 20 therefrom, said container comprising a flexible plate formed with a downwardly extending flange and having powder distributing orifices, a pocket open against the plate and secured to the plate under its outer edge the other end of the pocket being of 25 flexible material and a thin disk closing the end of the pocket, the material of the pocket being removably inturned under the lower edge of the disk, a spring arranged outside the container bearing against the under side of the flange.

- 20 2. A vanity box for containing loose powder having a bottom compartment and a cover, a powder container positioned in the bottom of the box and bodily removable 25 therefrom, said container comprising a flexible plate formed with a downwardly extending flange and having powder distributing orifices, a pocket open against the plate and secured to the plate under its outer edge the other end of the pocket being of flexible material and a thin disk closing the end of the pocket, the material of the pocket being removably inturned under the lower edge of the disk, a spring arranged outside the container bearing against the under side of the flange.

ble plate formed with a downwardly extending flange and having powder distributing orifices, a pocket of flexible material open against the plate and secured to the plate under its outer edge and a disk closing the 30 other end of the pocket, the material of the pocket being removably inturned under the lower edge of the disk, a spring arranged outside the container bearing against the under side of the flange, and resilient means 35 independent of the spring for removably holding the container and associated parts in the bottom of the box.

3. A loose powder holder comprising a 40 box and a cover therefor, and a powder container bodily removable from the box and including a distributing plate, and a pocket of flexible material secured to the under side of the plate and closed by a disk under which the edges of the pocket are removably 45 infolded.

In testimony whereof, I have hereunto set my hand.

LE ROY ROOT.
